UNITED STATES PATENT OFFICE.

MINARD A. POSSONS, OF CLEVELAND, OHIO.

RAIL CLAMPING OR FASTENING DEVICE.

SPECIFICATION forming part of Letters Patent No. 517,236, dated March 27, 1894.

Application filed November 20, 1893. Serial No. 491,457. (No model.)

To all whom it may concern:

Be it known that I, MINARD A. POSSONS, of Cleveland, in the county of Cuyahoga and State of Ohio, have invented certain new and 5 useful Improvements in Rail Clamping or Fastening Devices; and I do hereby declare the following to be a full, clear, and exact description of the invention, such as will enable others skilled in the art to which it pertains to 10 make and use the same.

My invention relates to improvements in rail-clamping or fastening-devices, and it consists more especially in simple and durable means for clamping or fastening the rails to 15 metallic ties.

In the accompanying drawings, Figure 1 shows the rails of a track fastened or clamped to a metallic tie, by my improved rail-clamping or fastening-devices, portions of the same 20 being in section to more clearly show the construction, and portions being broken away to reduce the size of the drawing. Fig. 2 is a perspective showing my improved rail-clamping or fastening-device before application. 25 Fig. 3 shows a rail in position upon the tie (the latter being in section), exhibiting also the manner of applying my improved rail-clamping or fastening-device.

My improved rail-clamping or fastening- 30 device, as it appears before it is applied, is exhibited in Fig. 2, and consists of two upright arms A connected by a web a, the web being enlarged upwardly between the arms, as at a', being separated from the arms a 35 suitable distance, as at a², for the purpose hereinafter made apparent, and being preferably somewhat undercut adjacent the arms, as at a³. The arms extend a suitable distance above the enlarged portion of the web, 40 and at their upper extremity terminate in jaws or laterally-projecting flanges A', said flanges projecting at right angles to the web, and the arms, opposite to the free extremities of jaws or flanges A' are rounded or cut 45 away, as at A².

The application of my improved rail-clamping or fastening device is illustrated in Figs. 1 and 3, and referring to which B represents a metallic tie that is preferably composed of 50 a channel-beam, U-shaped in cross-section,

and arranged with its web or central member b uppermost, and with its flanges b' resting upon the ground or bed underneath, the rails C resting upon the web or horizontal member of the tie. Said member of the tie, at the 55 edges of the base of the rails, is slotted, or perforated, as at b², for the insertion of the laterally-bent extremities or jaws of arms A of the clamping or fastening-device, the latter being applied, as shown in dotted lines 60 Fig. 3, the rounded portion A² of the arms of the clamping or fastening-device accommodating the insertion of said members into holes b². The size of web a a' of the clamping or fastening-device is such that when the 65 latter is in position relative to the tie preparatory to clamping or fastening the rail, the top thereof shall engage the under side of the top or horizontal member of the tie and the arms of the clamping or fastening-device 70 are then twisted to bring flanges or jaws A' thereof into engagement with the top surface of the base of the rails, as shown in Fig. 1, said arms of course contracting somewhat by thus twisting the same, and thereby causing 75 the aforesaid jaws or flanges to firmly clamp the rail upon the top of the tie. The portions of the top or horizontal member of the tie that form the outer side-walls of holes b² are preferably bent laterally and upwardly, 80 as at b³, so that when the rail is clamped or fastened to the tie the shoulders or abutments b⁴ presented by said upwardly-bent portions of the tie shall be in the same or approximately the same horizontal plane with 85 the edges of the base of the rail, and the size of holes b² is such that when the rail is secured in position the base of the rail shall not only be clamped on top by flanges or jaws A', but shall also be clamped at its edges; that 90 is, the holes referred to are of such size that the arms J of the rail-clamping or fastening-device, when twisted to clamp the rail, shall engage the respective shoulder or abutment b⁴ on the one side, and the adjacent edges of 95 the base of the rail on the opposite side.

The spaces a² had between the web and arms of the rail-clamping or fastening-device, and hereinbefore referred to, are for the purpose of accommodating the twisting of said 100

arms. The material of which the rail-clamping device is composed is preferably mild steel or Norway iron, or such other metal as will not be injured or have its durability affected by twisting the clamping-arms of the device as hereinbefore described. It will also be observed that shoulders or abutments b^4 of the tie form a railway-gage by which the rails of the track are laid.

10. What I claim is—

1. A rail-clamping or fastening-device consisting of two arms adapted to clamp the base of the rail and connected by a web, the free ends of the arms terminating in clamping-jaws and the connecting web being adapted to engage the underside of the rail-supporting-tie or member, the device being composed of such material as will accommodate the twisting of the arms and the web being separated a suitable distance from the arms to accommodate the twisting of the latter, substantially as set forth.
2. A rail-clamping or fastening-device consisting of two arms A, connected by a web, a , the free ends of the arms terminating in clamping-jaws and the connecting web being enlarged in the direction of said jaws and adapted to engage the under side of the rail-supporting tie or member, the device being composed of such material as will accommodate the twisting of the arms without mutilating or materially affecting the durability of the same, the enlarged portion of the web being separated a suitable distance from the arms to accommodate the twisting of the latter, and the jaws of the arms being adapted

to clamp the top and edges of the base of the rail, substantially as set forth.

3. A rail-clamping or fastening-device consisting of two arms A connected by a web a , the arms, at their free ends, terminating, respectively, in a laterally-projecting flange or jaw A' rounded or cut away, as at A², and the web being enlarged in the direction of said jaws, as at a' , with the enlargement separated from the arms, as at a^2 , the arms being composed of such material as to render the same capable of being twisted without materially injuring the durability of the device, substantially as and for the purpose set forth.

4. The combination with a rail and metallic tie for supporting the rail, the supporting-member, of said tie having holes, b^2 , and shoulders or abutments b^4 , formed thereon at the outer sides of said holes, of a rail-clamping or fastening-device consisting of two arms connected by a web, the web engaging the under side of the aforesaid member of the tie and the arms extending through the aforesaid holes and terminating at their upper extremities in jaws that engage the aforesaid shoulders or abutments on their one side and the adjacent edge of the base of the rail on the opposite side, substantially as shown, for the purpose specified.

In testimony whereof I sign this specification, in the presence of two witnesses, this 16th day of October, 1893.

MINARD A. POSSONS.
